UNITED STATES PATENT OFFICE.

ANTHONY VANDERVELD, OF GRAND RAPIDS, MICHIGAN, ASSIGNOR TO CLIPPER BELT LACER COMPANY, A CORPORATION OF MICHIGAN.

TOOL FOR HANDLING BELT-STAPLES.

1,238,965.

Specification of Letters Patent. Patented Sept. 4, 1917.

Application filed September 11, 1916. Serial No. 119,885.

To all whom it may concern:

Be it known that I, ANTHONY VANDERVELD, a citizen of the United States of America, residing at Grand Rapids, in the county of Kent and State of Michigan, have invented certain new and useful Improvements in Tools for Handling Belt-Staples; and I do hereby declare the following to be a full, clear, and exact description of the invention, such as will enable others skilled in the art to which it appertains to make and use the same.

This invention relates to an appliance for containing a quantity of belt hooks or staples and by means of which said staples may be inserted one at a time in the slots of a slotted holder which forms a part of a tool for affixing the staples in spaced apart relation to the end of a belt. Heretofore it has been customary to either place the staples by hand one at a time in said holder or to attach the staples in proper spaced apart relation to a card or similar mount whereby the staples may be placed in the slotted holder by transferring the mount with attached staples to the tool. The former method is objectional by reason of the amount of time which is consumed while in the latter the card must necessarily be formed of some material such as paper or the like which may be easily cut to obtain a required number of staples to be placed in the slotted holder at any time, the card, being easily broken and destroyed and a considerable number of the staples rendered useless and wasted so far as belt attaching value is concerned. It is the object and purpose of my invention to provide a device for very readily inserting the staples in the slotted holder, as few or as many as may be desired, and at the same time provide an appliance in which none of the staples are lost or in any manner made useless for belt connecting purposes. Further objects and purposes of the invention consist in many novel features of construction and operation and arrangement of parts for practically attaining this end in a simple and efficient manner and in the production of a tool for this purpose which may be produced at a low cost of manufacture.

I have embodied my invention in a device which is disclosed in the accompanying drawings, in which:

Figure 1 is a perspective view of the de-

vice shown in use in connection with a well known construction of tool used for attaching belt staples to the ends of belts.

Fig. 2 is a full size side elevation of the device.

Figs. 3 and 4, respectively, are end elevations from opposite ends of the construction shown in Fig. 2.

Fig. 5 is a side elevation from the side opposite to that shown in Fig. 2.

Fig. 6 is an end elevation from the left hand end of the construction shown in Fig. 5 with parts removed and broken away to properly disclose the interior structure.

Figs. 7 and 8 are side and edge views of a detail of the structure, the use of which will later appear, and

Figs. 9 and 10 are side and edge views of the movable feed device which is manually operated to eject the staples one at a time.

Like reference characters refer to like parts throughout the several views of the drawings.

In the construction of the staple handling appliance a bar 1 of metal is provided which at one end has a section 2 integral therewith and turned at right angles to the length of the bar. At each side of the section 2 blocks 3 and 4 of metal are placed. A trough-like housing 5 of sheet metal formed with a curved central portion and diverging sides lies lengthwise of the bar 1 being spaced a short distance therefrom and at one end has spaced apart extensions 6 which cover the outer faces of blocks 3 and 4 heretofore described. A member formed of sheet metal and having sides 7 and 8 positioned at right angles to each other is placed so that the side 7 covers the front edges of blocks 3 and 4 and the section 2 while the side 8 lies over the section 6 adjacent the block 3. The side 8 is extended downwardly and inwardly at an angle as shown at 9, part 9 paralleling the adjacent side of the housing 5. Bolts 10 are passed through the blocks 3 and 4 and the section 2, sections 6 and through the side 8 of the member heretofore described thereby binding them together and holding them in fixed relation with respect to each other.

The trough-like housing 5 is adapted to receive a plurality of wire belt staples 11 of the well known Webb type such staples each having a curved central bight with diverging legs extending in the same direction

from the bight and attaching prongs turned inwardly toward each other from the free ends of the legs. These staples are adapted to pass over the bar 1 moving freely between such bars and the sides of the housing 5. A follower 12 also trough-like in form is made from sheet metal and lies between the bar 1 and the housing 5, it having a projection 13 at its rear end to which may be attached one end of a coil tension spring 14. The opposite end of the spring is fastened to a pin 15 secured in any suitable manner to the forward end of bar 1 substantially at its juncture with the section 2 thereof. This spring under tension serves to press the staples 11 forward so that the attaching prongs and adjacent ends of the legs of the foremost staple in the device bear against the lower end of the side 7 which terminates a short distance above the bight of said staple. The bight of the forward staple is pressed against the lower inturned end 16 of a lever 17 pivotally mounted upon an ear 18 integral with and turned forward from the side 7 heretofore described. Such side 7 also has a depending tab 19 directly underneath which the end 16 of lever 17 is adapted to pass to engage with the bight of the foremost staple in the appliance. On the side of the appliance opposite the part 8 a feed slide 20 is mounted, it having a slot 21 therein through which passes one of the bolts 10 the movement of the slide being controlled in amount by said bolt and slot. The slide is turned at its upper end to form a right angular extension 22 which lies over and a distance above the upper ends of blocks 3 and 4 and the extension 2. Depending from part 22 is a plunger 23 which at its lower end is narrowed to form an ejecting finger 24. The plunger is guided between blocks 3 and 4 at the sides and between parts 2 and 7 at the rear and front, the extension 2 being cut away sufficiently to permit the up and down movements of the plunger. The plunger is held normally in upper position by spring 25 which is placed around the plunger and interposed between the extension 22 and the upper ends of blocks 3 and 4 as best shown in Fig. 5. The forward edge of the slide 20 has a bearing edge 26 directly above which is a similar edge 27 located in a plane slightly back of the edge 26. The upper rearwardly turned end 28 of the lever 17 is adapted to bear in its normal upper position against the edge 26 whereby the lower end 16 of lever 17 is forced against the bight of the foremost staple; but upon downward movement of the slide the end 28 is permitted to move slightly to the rear and against the bearing edge 27, the lower end 16 of the lever moving outwardly and permitting the foremost staple to occupy a position with its bight directly under the ejecting finger 24.

An inclined cam 29 is formed at the opposite edge of slide 20 against which the upper rounded end 30 of a lever 31 bears, this lever being pivoted between its ends to the adjacent side 6. Its upper end is normally drawn against the cam 29 by a spring 32 which at one end is connected to a pin on the lever and at its opposite end to an ear 33 turned from the side 6 as shown. The lower end of lever 31 is bent, as shown at 34, substantially parallel to the adjacent side of the trough-like housing 5 and a lever 35 is pivotally connected to the lower end of lever 31 and at its forward end formed with a dog 36. At its rear end it is bent at 37 as indicated to the rear of lever 31 to provide an ear for attachment of one end of the coil spring 38 which at its opposite end is secured to a pin mounted upon the lever 31 whereby said lever 35 is held from aimless movement with respect to the lever 31.

In practice this appliance is adapted to eject staples one at a time and properly position them in a staple attaching tool for belts. A well known form of tool of this character of the type shown in United States Patent No. 1,012,614, is shown in Fig. 1 including a base 39 on which two bars 40 and 41 are secured, the former being slotted to provide a plurality of spaced apart tongues 42 between which the belt staples are to be entered. The bar 41 has an inclined surface and my device is adapted to be laid against this surface, the part 9 sliding thereover and with the curved section of the trough-like housing 5 resting against the forward edges of the tongues 42. When so positioned dog 36 on lever 35 enters a slot between two of the tongues 42. The appliance is held in the hands of the operator, the right hand grasping the housing 5 and pressing forward slightly so as to hold the dog 36 in contact engagement with a tongue 42. The left hand is so positioned that the thumb bears against the section 22 of the ejector slide 20 and the index finger is engaged with the nut on the upper bolt. When in this position the operator may exert force with the thumb of the left hand to move the ejector slide 20 toward bar 40. With the beginning of the movement of the ejector slide, lever 17 is released sufficiently to permit the forward movement of the foremost staple in the appliance into alignment with the ejecting finger 24, the spring 14 moving the staple as soon as the end 16 of lever 17 is released. At the same time lever 31 is operated. As the dog 36 of lever 35 is engaged against a tongue 42 the result is that the appliance as a whole is moved one step to the rear along bar 40. As this movement is completed the ejecting finger 24 engages with the foremost staple and with the completion of the downward movement of the ejector slide a staple is carried into a slot between two of the

tongues in front of the lever 35. With the release of the ejector slide spring 25 returns it to normal position permitting lever 31 to take its normal position under the influence of spring 32 whereupon the dog 36 on lever 35 moves rearwardly one space and occupies the slot one space to the rear of that which it previously occupied. The operation may be repeated indefinitely and as many staples as required placed in succession in consecutive slots in the bar 40. For convenience I have formed a scale 43 at one side of the housing 5 and by applying a belt end to this scale an operator may know at a glance how many staples to transfer to the attaching tool. In this connection it may also be noted that when a belt staple is passed from the device to a position between two of the tongues 42 the lower leg of the staple which lies against the surface of the block 41 is immediately in front of the forward edge of the part 9 and it is therefore impossible to move the appliance forward against this staple. An attempted entrance of a second staple into a particular slot which has received a staple cannot take place and furthermore if at any time a failure to enter a staple into a slot should occur the tool can be immediately positioned for this slot by pressing the forward edge of the part 9 against the leg of the staple which is in the slot immediately ahead of the one to be filled.

With a device of the character described a plurality of belt holding staples may be entered between the bar 1 and the housing 5 and be held and protected absolutely from loss. The staples can be supplied to the attaching tool very quickly and easily and after they are placed in the tool there is no necessity for removal of any card or other mount from the staples as is now almost universally necessary. The tool is of simple construction and may be manufactured at a very low cost. Changes in construction may be resorted to without departing from my invention defined in the appended claims and I accordingly do not wish to be limited to the exact structure shown, but consider myself entitled to all modifications falling within the scope of the appended claims.

I claim:—

1. In a device of the character described, a bar having a right angular extension at one end, a block at each side of the extension, a trough-like housing positioned lengthwise of and spaced from the bar, sides extended at right angles from said housing at one end and passing alongside the blocks means securing said sides, blocks and extension together, a spring operated follower located between the bar and housing, a plate slidably mounted on one of said sides of the housing, a plunger connected to the plate and positioned in front of the extension to

said bar, an ejecting finger at the end of the plunger, a plate covering the front edges of the blocks and said extension, said plate terminating short of the bend in the housing, and a lever pivotally mounted on the plate and having one end positioned directly in front of the opening between the bar and housing and the other end engaged with an edge of the slidably mounted plate.

2. A device of the character described comprising, a trough-like container for belt staples each formed with a central curved bight and with diverging arms terminating in attaching prongs extending from the bight, ejecting mechanism for ejecting the staples from the container one at a time to a holder having spaced slots for receiving the staples, and means on the device operated by the ejecting mechanism for engaging with said slotted holder to move the device step by step along said holder with successive operations of the ejecting mechanism.

3. A device of the character described comprising, a container for receiving a quantity of belt staples, an ejecting mechanism for ejecting the staples one at a time, and adapted to deliver them to a holder having spaced tongues separated by slots for receiving the staples, and means on the device operated by the movement of the ejecting mechanism for engaging with the tongues of said holder to move the device step by step along the length of said holder with successive operations of the ejecting mechanism.

4. A device of the character described adapted to be applied to a slotted staple holder, said device including means for receiving a quantity of belt staples, an ejecting means manually operable toward the slotted holder for ejecting staples one at a time from the device to said holder, a lever pivotally mounted on the device and having one end bearing against an element of the ejecting means and operable thereby, and means mounted on the opposite end of the lever adapted to engage with the slotted holder to move the device lengthwise thereof step by step with successive operations of the ejecting means.

5. A device of the character described adapted to be applied to a slotted staple holder, said device including a container for a quantity of belt staples, a manually operable ejecting means mounted at one end of the container for ejecting staples from the container one at a time to the slotted holder, means for moving the staples in the container into position to be ejected by the ejecting means, means on the device to engage with the slotted holder, and means operated with the ejecting movement of the ejecting means for actuating said holder engaging means to move the device one step

equal to the distance between successive slots with each operation of the ejecting means.

6. In a device of the character described, a container for belt staples, a plate mounted to move at right angles to the length of said container, means for moving the staples lengthwise of the container toward one end thereof; a plunger terminating in an ejecting finger secured to and movable with the plate, said finger adapted to engage with and eject a staple from the container, a lever pivotally mounted between its ends and bearing against an inclined edge of the plate, means to hold one end of the lever against said edge, and a second lever terminating at one end in a dog and pivotally mounted on the opposite end of said first mentioned lever to be operated thereby to move the device.

7. In a device of the character described, a container adapted to hold a quantity of belt staples positioned side by side lengthwise thereof, a plate slidably mounted at one end of the container to move in a direction at right angles to the length of said container, a plunger secured to and movable with the plate, a spring tending to hold the plate and plunger at one extreme of their movement, an ejecting finger at the end of the plunger adapted to pass across one end of the container and eject the end staple therefrom, means to move the staples lengthwise of the container toward the ejecting finger, a stop plate against which portions of the end staple contact, and a lever mounted on said stop plate and having one end passing around the end of said plate to engage with another part of the end staple and normally prevent ejection thereof, the other end of said lever engaging against an edge of said slidably mounted plate, said edge of said plate having a depression therein to permit pivotal movement of said lever to free the end staple for ejection on operation of said slidably mounted plate.

8. In a device of the character described, a container for belt staples comprising a trough-like housing having a curved central portion and diverging sides, extensions to said sides at one end of the housing located substantially at right angles to the length of the housing, a bar positioned lengthwise of the housing and spaced therefrom, said bar having an extension located at right angles to the length of the bar and positioned between said extensions of the sides of the housing, spacing blocks between said extensions of the bar and housing, a member comprised of plates positioned at right angles to each other, one of said plates being a front plate positioned to cover the front edges of the extension of the bar and said blocks, and the other plate lying over one

of the extensions of the housing sides, bolts passing through said last plate, the blocks and extensions to the bar and housing, a trough-like follower located between the bar and housing, a spring tending to move the follower toward the extension to the bar, a plate slidably mounted on and partially covering the other extension to the side of the housing, said slidably plate at its rear edge having an inclined cam and at its opposite edge being provided with two bearing surfaces one in a plane back of the other, a lever pivotally mounted on said front plate and having its upper end engaged against the last mentioned edge of the sliding plate and its lower end turned in under the front plate directly in front of the front outlet to the housing, a second lever pivotally mounted on the housing and having its upper end bearing against the inclined cam, a spring to keep said end against the cam, a lever provided at its forward end with a dog and pivotally mounted on the lower end of the second lever, a spring connecting the other end of said last named lever to said second lever, an extension to the sliding plate turned over the upper ends of said blocks and extension to the bar, a plunger connected to said plate extension and guided between the blocks and the extension to the bar and the front plate, a spring around the plunger between the upper ends of the blocks and the extension to the sliding plate, and an ejecting finger formed at the lower end of the plunger.

9. A device adapted to insert belt staples into the slots of a slotted staple holder, comprising a container for a quantity of belt staples, an ejecting means for ejecting staples from the container, and means for moving the device with reference to the slotted staple holder step by step as the staples are ejected to place them successively in the slots adapted to receive them.

10. A device of the character described, comprising a container for receiving a quantity of belt staples, means including an ejecting plunger for ejecting the staples one at a time from the container, said plunger being adapted to pass across an open end of the container, and a lever mounted on the device and having one end normally engaging against the foremost staple in the container to hold it and the remaining staples against accidental passage from the container.

11. A device of the character described, comprising a container having open ends, said container being adapted to receive a quantity of belt staples, a spring operated follower entered into one end of the container to force the staples toward the opposite end, a plunger mounted at said opposite end of the container and arranged to be moved across the end thereof to eject the foremost staple from the container, a lever

- pivotedly mounted on the device having one end turned under the end of the plunger to engage against the foremost staple in the container, and a cam associated with and movable with the plunger and against which the other end of the lever bears, substantially as described. 5
12. A device adapted to insert belt staples into the slots of a slotted staple holder, comprising a container for a quantity of belt staples, an ejecting means for ejecting staples from the container, means for moving the device with reference to the slotted staple holder step by step as the staples are ejected to place them successively in the slots adapted to receive them, and means for operating said moving means during the initial portion of the movement of the ejecting means. 10
13. A device adapted to insert belt staples into the slots of a slotted staple holder, comprising a container for a quantity of belt staples, ejecting mechanism for ejecting staples one at a time from the container, and means operated by the ejecting mechanism for moving the device with reference to the slotted holder step by step as the staples are ejected to place them successively in the slots adapted to receive them. 15
14. A device adapted to insert belt staples into the slots of a slotted staple holder, comprising a container for a quantity of belt staples, an ejecting mechanism including a plunger for ejecting staples one at a time from the container, a cam plate associated 35 and movable with the plunger, a lever pivotedly mounted on the device and having one end engaging against the cam plate, and a dog mounted on the lever for engaging with the slotted holder to move the device along 40 said slotted staple holder step by step with successive operations of the ejecting mechanism, substantially as described. 45
15. A device adapted to insert belt staples into the slots of a slotted staple holder, comprising a container for a quantity of belt staples, an ejecting mechanism including a plunger for ejecting staples one at a time from the container, a cam plate associated 50 and movable therewith, a lever pivotedly mounted on the device and having one end engaged against one edge of the cam plate, a dog mounted on the lever for engaging with the slotted holder to move the device along 55 said slotted holder step by step with successive operations of the ejecting mechanism, and a second lever pivotedly mounted on the device and having one end engaging against the opposite edge of the cam plate and the other end turned under the end of the plunger to hold the staples against accidental displacement from the container, substantially as described. 60

In testimony whereof I affix my signature.

ANTHONY VANDERVELD.
